CLAIM

The ornamental design for an angle adjuster of bicycle saddle, as shown and described.

DESCRIPTION

FIG. 1 is a perspective view of an angle adjuster of bicycle saddle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of an embodiment of the angle adjuster of bicycle saddle showing my new design.

The dash-dot-dash lines depict boundary lines of the angle adjuster of bicycle saddle and form no part of the claimed design. The dash-dot broken lines depict portions of a bicycle saddle for the purpose of illustration that form no part of the claimed design.
